CLAIM

The ornamental design for an electronic display for a wearable device presenting a graphical user interface, as shown and described.

DESCRIPTION

FIG. 1 is a front view of a first image of a first embodiment of an electronic display for a wearable device presenting a graphical user interface, showing our new design; FIG. 2 is an enlarged front view taken from FIG. 1; FIG. 3 is a front view of a second image of the first embodiment;

FIG. 4 is an enlarged front view taken from FIG. 3; FIG. 5 is a front view of a first image of a second embodiment of an electronic display for a wearable device presenting a graphical user interface, showing our new design; FIG. 6 is an enlarged view taken from FIG. 5; FIG. 7 is a front view of a second image of the second embodiment; and, FIG. 8 is an enlarged view taken from FIG. 7.

The appearance of the graphical user interface transitions sequentially between the images shown in FIGS. 1 and 3, FIGS. 2, and 4, FIGS. 5 and 7, and FIGS. 6 and 8. The process or period in which one image transitions to another forms no part of the claimed design.

The broken line showing of the electronic display for a wearable device presenting a graphical user interface is for the purpose of illustrating portions of the electronic display for a wearable device presenting a graphical user interface and forms no part of the claimed design.

The dot-dash broken line encircling the enlarged portion forms no part of the claimed design.
